UNITED STATES PATENT OFFICE.

ALBERT RONTKE, OF ELIZABETH, NEW JERSEY, ASSIGNOR TO THE SINGER MANUFACTURING COMPANY, A CORPORATION OF NEW JERSEY.

NEEDLE-BAR MECHANISM FOR SEWING-MACHINES.

SPECIFICATION forming part of Letters Patent No. 712,853, dated November 4, 1902.

Application filed November 26, 1901. Serial No. 83,769. (No model.)

To all whom it may concern:

Be it known that I, ALBERT RONTKE, a citizen of the United States, residing at Elizabeth, in the county of Union and State of New Jersey, have invented certain new and useful Improvements in Sewing-Machines, of which the following is a specification, reference being had therein to the accompanying drawings.

10 This invention relates to an improvement in that class of multiple sewing-machines in which the loop-taker coöperates with two or more reciprocating needles having coincident or parallel axes of motion in the formation of 15 stitches; and it has for its object to so time the relative movements of the needles that each is brought independently into operation with the common loop-taker. Heretofore a similar result has been attained in twin-needle 20 machines by means of a common needle-bar carrying two needles of different lengths, of which the longer was disposed farther from the loop-taker in its forward or loop-seizing movements. Such arrangement had, however, 25 the disadvantage of requiring an excessive needle-bar movement to afford sufficient dwell of the longer needle beneath the cloth-plate to expose its loop to the loop-taker after the latter has taken that of the shorter 30 needle and also to provide clearance for the work above the cloth-plate and beneath the longer needle at the upper end of its stroke.

It is the object of the present invention to obviate these defects.

35 The invention therefore consists in mechanism whereby each of the needles is given an equal length of movement; but the needle or needles farther from the initial loop-seizing position of the loop-taker receive a dwell 40 at both ends of their stroke and an accelerated movement intermediate thereto. By this means two or more needles of equal length may be employed in conjunction with needle-bars receiving comparatively short reciprocations of equal length regardless of the gage 45 of the seam to be produced by said looper and coöperating needles.

While the present improvement is designed more particularly for use in connection with 50 twin-needle machines, it is obvious that it is

equally well adapted for all multineedle-machines in which a loop-taker or loop-takers of any description coöperate each with two or more needles in forming a seam and that its adaptation is not limited in its broadest aspect to needle-bar mechanisms, as it may be readily adapted to any other portions of the machine in which two or more parallel or axially-coincident reciprocating members are required to have relatively differential reciprocating movements of equal extent and in equal times.

The annexed drawings illustrate the invention as embodied in a twin-needle machine of the general construction disclosed in the 65 United States Patent No. 568,702, granted to me September 29, 1896, in which the loop-taking member consists of an oscillating thread-carrying looper.

Figure 1 is a front side view of the machine 70 with the outer portion of the arm partially in section to expose the needle-bar-actuating mechanism, and Fig. 2 an end view of the same with the face-plate partially broken away to expose the same parts. Fig. 3 is a 75 diagrammatic view showing the needle-bar mechanism in its intermediate position in full lines and in extreme positions in dotted lines. Fig. 4 is a face view of the needle-bar mechanism and the stitch-forming devices in the 80 position assumed when the looper has taken the loop of the needle-thread from one needle and is about taking the loop from the other needle; and Fig. 5, an elevation of the same parts, showing the needle-bar mechanism in 85 edge view. Figs. 6 and 7 are elevational views similar to Figs. 4 and 5, showing the relation of the parts when the needles are descending, the first having passed through the looper-loop and the second being about to 90 enter the same. Figs. 8 and 9 are transverse sections on lines 8 8 and 9 9 in Figs. 4 and 5, respectively.

A denotes the work-plate; B, the bracket-arm of the machine, said arm having at its 95 front end the usual head b, affording bearings for the presser-bar c and the main or primary-needle bar d, which is longitudinally grooved or channeled to receive and guide the shorter auxiliary or secondary-needle bar e, the axis 100

of motion of which is substantially coincident or parallel with that of the primary-needle bar *d*.

C is the needle-bar-actuating rock-shaft, 5 journaled in the upper part of the arm *B* and carrying at its front end the crank *f*, having the crank pin or stud *g*, to which is jointed the upright arm *h* of a bell-crank or elbow lever or rocker which is fulcrumed at its elbow or apex upon a pivotal pin or stud *j*, carried by a collar *k*, fixed upon the primary-needle bar *d*. The lateral arm *i* of the bell-crank or rocker carries a pin or stud *l*, jointed to one end of a link *m*, whose other end embraces a pivotal pin *o*, carried by a lateral lug projecting from a collar *p*, fixed to the secondary-needle bar *e*, but embracing loosely the primary-needle bar *d* below its fixed collar *k*. Each of the needle-bars is provided 10 in its lower end with the usual needle-socket, in which is clamped a needle *n* by means of a set-screw *s*, the auxiliary-needle bar having a lateral boss or projection *q*, to which is attached a band or strap *r*, embracing the primary-needle bar and slotted to accommodate 15 its clamp-screw.

The needles are set in their respective bars in such manner that their eyes will be at the same level when at the ends of their movement and are disposed in a vertical plane transversely of the feed to coöperate with a loop-taker operating in substantially the same plane and herein shown as consisting in an oscillating thread-carrying looper *L* of well-known form deriving its oscillatory and needle-avoiding lateral movements from the main shaft *D*.

In the operation of the machine the arm *h* of the bell-crank or rocker serves as a link 40 through which the primary-needle bar *d* receives the usual reciprocating movement from the actuating-crank *f*, and the arm *i* constitutes an offset therefrom, the elevation of which in relation to that of the fulcrum varies with the inclination of the arm *h* from the vertical as determined by the position of the actuating-crank, the constantly-changing difference in relative heights of the arm *i* and the fulcrum *j* determining the degree 45 of variation in the heights of the needles in relation to the cloth-plate. Thus by reference to Fig. 3 it will be seen that the arm *h* is vertical in its extreme upper and lower positions and that it becomes inclined to the right 50 in constantly-increasing degree until the crank *f* reaches its intermediate or horizontal position, wherein it attains its maximum inclination, from which position its inclination decreases in similar manner throughout the 55 remainder of its descending movement, the arm *i* following such motions and through the link *m* and collar *p* causing a corresponding axial movement of the auxiliary-needle bar in relation to the primary-needle bar. 60 The ascent of the crank *f* to its upper position obviously effects similar variations in the ascent of the needle-bars. It is evident

that in the lower portion of the needle-bar movement, which only affects the loop-taking operations of the stitch-forming members, 70 the lateral arm *i* of the bell-crank or rocker has a dip which constantly diminishes as the crank *f* descends below its intermediate position and similarly increases during the rising motion of the crank. Thus while the 75 maximum advance of the auxiliary needle in relation to the primary needle is gradually compensated for by its slower progress in the lower portion of its descent it enters the looper-loop sufficiently in advance of the primary needle, as indicated in Figs. 6 and 7, to enable the looper to recede at the same time as would be possible in case the primary needle only were employed. In corresponding manner the auxiliary needle lags behind 80 the primary needle in their ascent, as indicated in Figs. 4 and 5, to allow sufficient time for the point of the looper to advance from the former to the latter, so as to enable the looper to seize the auxiliary-needle thread 85 loop after having taken the primary-needle thread loop.

By the improvement as above described not only is provision made for a minimum needle-bar stroke for multineedle-machines of the 90 class described, but the loop-taking operations are rendered certain, owing to the dip of the needles being equal in the needle-loop-taking positions, and consequently to the equal lengths of thread from the needle-eyes 95 to the cloth-plate from which such loops are formed.

While the proportion and arrangement of parts herein shown and described are considered preferable for reasons heretofore given, 105 it is obvious that they may be widely varied to suit other conditions and requirements, and the invention is not, therefore, limited to the specific construction, proportion, and arrangement of parts herein set forth. It is 110 evident that resetting the crank *f* upon its shaft *C* and correspondingly changing the lengths of the upright arm *h* and link *m* would have the effect of varying the relative positions of the needles at the opposite ends 115 of their stroke, while a change in the relative lengths of the lateral arm *i* of the bell-crank or rocker and the actuating-crank *f* would produce a corresponding variation in the 120 relative movements of the needles.

It is to be understood that the terms "bell-crank," "elbow-lever," and "rocker" as used herein are intended to cover all devices for transmitting and redirecting reciprocating motions, and therefore apply to any members, each of such points being out of line with the fulcrum and the other of said points.

Having thus described my invention, I claim and desire to secure by Letters Patent—

1. In a sewing-machine, the combination with a plurality of reciprocating members arranged to move in parallel lines, of a two-armed rocker fulcrumed upon one of said

members and bodily movable therewith, an actuating device movable in a curved path and jointed to one arm of said rocker, the other arm of said rocker being connected 5 with the other or others of said reciprocating members from a point of said other arm distant from the line of travel of said members.

2. In a sewing-machine, the combination with a plurality of independently-movable 10 needle-bars and a thread-carrying looper coöperating with the needles of said needle-bars, of means, connected with said needle-bars, for causing the same to reciprocate in the same direction at the same time, but at varying 15 speeds; so that the needles of said needle-bars, while starting downward from the same level will be at different levels during certain points of their travel.

3. In a sewing-machine, the combination 20 with a plurality of independently-movable needle-bars and a thread-carrying looper coöperating with the needles of said needle-bars, of means, connected with said needle-bars, for causing the same to reciprocate in 25 the same direction at the same time, and to perform movements of equal lengths, but at varying speeds; so that the needles of said needle-bars, while starting downward from the same level will be at different levels during 30 certain points of their travel.

4. In a sewing-machine, the combination with a plurality of independently-movable needle-bars and a thread-carrying looper coöperating with the needles of said needle-bars, of an operating mechanism for said 35 needle-bars whereby they will be caused to perform simultaneous reciprocating move-

ments in the same directions and of equal extent and at equal times, but at different speeds during portions of their movements. 40

5. In a sewing-machine, the combination with a plurality of independently-movable needle-bars and a loop-taking device coöperating with the needles of said needle-bars, of a two-armed rocker fulcrumed upon one of 45 said needle-bars and bodily movable vertically therewith, an actuating device for said rocker movable in a curved path and connected with one arm of said rocker, the other arm of said rocker being connected with the 50 other or others of said needle-bars; whereby reciprocating movements of equal length and in equal times, but at differential speeds, will be imparted to said needle-bars.

6. In a sewing-machine, the combination 55 with two independently-movable needle-bars and a loop-taking device coöperating with the needles of said needle-bars, of a bell-crank or elbow lever fulcrumed on one of said needle-bars and bodily movable therewith, a rock-shaft having an arm to which one arm of said elbow-lever is jointed, and a link connecting the other arm of said bell-crank or elbow lever with the other of said needle-bars; whereby reciprocating movements of equal length and in equal times, 60 but at differential speeds, will be imparted to said needle-bars.

In testimony whereof I affix my signature in presence of two witnesses.

ALBERT RONTKE.
